(57) **CLAIM**

I claim the ornamental design for an all-position truck tire, as shown and described.

DESCRIPTION

FIG. 1 is a perspective view of the all-position truck tire according to my new design, it being understood that the tread pattern is repeated throughout the circumference of the tire;

FIG. 2 is a front elevational view thereof;

FIG. 3 is a right side view thereof, with the left view being a mirror image of the right view; and,

FIG. 4 is an enlarged partial perspective view, showing particular detail of the tread pattern thereof.

The dashed-pattern broken lines illustrated show portions of the all-position truck tire that form no part of the claimed design.

The dashed-pattern broken lines used for demarcation of enlarged portions of the all-position truck tire form no part of the claim.

The dash-dot-pattern broken line in the drawing views represents the boundaries of the claimed design.

1 Claim, 4 Drawing Sheets
